PNEUMATIC THREAD EXTRACTOR FOR
LOOMS

Richard G. Turner, Worcester, Mass., assignor to
Crompton & Knowles Loom Works, Worcester,
Mass., a corporation of Massachusetts

Application July 31, 1939, Serial No. 287,465

14 Claims. (CL. 139—256)

This invention relates to improvements in pneumatic thread extractors for looms and it is the general object of the invention to provide a simplified pneumatic system for removing the thread extending from the selvage to the outgoing bobbin at the time of transfer.

In bobbin changing looms the insertion of a fresh reserve bobbin and the removal of the depleted bobbin are accomplished at the same time, usually by a single stroke of the transferrer arm, and the thread attached to the outgoing bobbin extends from the selvage into the shuttle box and through the shuttle eye. Unless this thread is removed from the path of the shuttle it is likely to be drawn into the warp shed to produce a double pick. I have heretofore proposed pneumatic means for removing this thread including a tube mounted on a carrier arm supported by a pivot located behind the lay. It is an important object of my present invention to eliminate the supporting arm and construct the tube so that it derives support directly from the pivotal mounting. In this way I eliminate one of the parts heretofore employed.

In my present invention I provide a tube having an intake mouth at its lower end and bend the tube upwardly and backwardly toward the pivotal mounting thereby providing a curve in the interior of the tube which I find increases the frictional hold on the thread. In constructing the tube so that it has direct supporting relation with the pivotal mounting I therefore also achieve an increased tension or drag on the thread.

It is a further object of my present invention to improve the pivotal mounting with a view to insuring retention of the pneumatic tube in any position to which it may be moved. In carrying this feature of my invention into effect I provide a friction device which yieldingly holds the tube either raised or lowered, and I prefer to use a sheet of inherently resilient material, such as natural or artificial rubber, so positioned as to exert a compressing force on the relatively movable friction surfaces. I have found for instance that a stationary metal stand having a friction surface to engage a fiber disk beside which is a disk of resilient material will operate satisfactorily to hold the tube in position when pressure is exerted on the resilient disk by means of a bolt or the like.

It is desirable that the intake mouth be moved to a position in alignment with the thread extending from the selvage into the shuttle box and it is a further object of my present inven-

tion to provide means for lowering the tube including a part which is moved by but adjustable with respect to the transferrer arm. This part includes an arm capable of having a plurality of fixed angular positions with respect to the transferrer arm and positioned for engagement with the pneumatic tube. This latter feature has advantages in distributing wear but I do not wish necessarily to be held to it in the practice of my invention.

In pneumatic thread extractors of the type already mentioned it has been proposed heretofore to provide a baffle wall or plate to project into deformable material extending across the lay for the purpose of guiding the thread toward the intake mouth. These baffle plates have been formed as separate parts to be attached to the extractor tube and it is a further object of my present invention to eliminate these plates by shaping the tube in such a way that a portion of it will extend horizontally over the deformable material and serve the same purpose as the previously proposed guards or plates. To enable the tube to perform this additional function of guarding the thread I extend the lower end of the tube rearwardly and thereby produce an additional bend in the tube which increases the frictional hold which the tube has on the thread in the tube.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is an end elevation of my invention viewed from the center of the loom with the pneumatic tube in normally raised position, parts being in section,

Fig. 2 is a detailed vertical section on line 2—2 of Fig. 1,

Fig. 3 is a view similar to a portion of Fig. 1 but showing the tube moved to thread removing position,

Fig. 4 is a bottom plan view of the lower end of the tube, showing the intake mouth and guide tongue, taken in the direction of arrow 4, Fig. 1,

Fig. 5 is a plan view of parts of the lay, shuttle and thread extractor, and

Fig. 6 is a view similar to a part of Fig. 3 but showing the extractor tube in engagement with the pile tufts on the lay.

Referring to the drawing, I have shown a loom frame 10 including a breast beam 11 on which is

mounted a magazine stand 12. A magazine designated generally herein at M and similar to that shown in my prior Patent No. 2,128,974 includes in its construction a transerrer arm 13 5 movable pivotally about a fixed stud 14 by a latch 15 normally below the path of a bunter 16 on the lay L. The latter is reciprocated in the usual manner by a connector 17 and moves forwardly or to the right as viewed in Fig. 1 toward transfer position each beat of the loom.

The magazine may rock around a pivot 18 to place its delivery throat 19 over the shuttle S preparatory to transfer. The magazine is of the type which supplies two distinctive kinds of weft 15 and for a further description of the mechanism thus far described reference may be had to my previously mentioned patent.

The upper part of the lay has a body of deformable material such as pile fabric indicated at 20 25 across which the weft thread W extends from the selvage into the shuttle box 26. This material 25 may be substantially the same in function as that set forth in my co-pending application Serial No. 190,637 to which reference may be had 25 for the general features of my present invention. The loom frame has secured thereto a bracket 28 mounted for vertical and horizontal adjustment by means of a bolt 29 and the vertical and horizontal slots 30 and 31, respectively, in the 30 bracket and loom frame. A forwardly extending arm 32 of the bracket affords support for a rocking arm 33 to be described more in detail herein-after and the upper end of which has a web 34 for engagement with a resetting screw 35 adjustable horizontally and transversely of the lay. This screw engages the web 34 on the backward stroke of the lay immediately following the transferring operation of the loom to return arm 33 to the normal position shown in Fig. 1.

40 The matter thus far described may be similar to the construction shown in my prior patent and in the previously identified co-pending application. It is thought sufficient for present purposes to state that when a transferring operation of the 45 loom is called by weft exhaustion the magazine will place a reserve bobbin under the transerrer arm 13 and that the latter will descend by engagement of the bunter 16 with the temporarily raised latch 15 as the lay approaches its front 50 center position, thereby effecting counter-clockwise angular motion of the transerrer arm around its pivot 14 to the position shown in Fig. 3.

In carrying my present invention into effect I provide a pneumatic tube 40 the forward end of 55 which is bent down as at 41 and then rearwardly as at 42. The rear of the tube is closed by a plate 43 from which projects a downwardly and forwardly extending guide tongue 44 intended to move forwardly through the deformable material 60 25. An intake mouth 45 in the lower rear part of section 42 is located over the tongue 44 and affords access to the interior of the tube.

From the vertical section 41 the tube extends 65 rearwardly as at 46 and terminates in an upwardly bent part 47 fitted to a pneumatic tube 48. The latter is connected to a vacuum pump to create an indraft of air into the intake mouth as the lay moves rearwardly, all as described in my co-pending application Serial No. 190,637.

70 In order to hold the tube in position I provide the construction shown in detail in Fig. 2. The rocking arm 33 has a bore 50 through which the straight part 46 of the tube extends and in which it is held in adjusted horizontal position by set 75 screw 51 threaded into the arm. The arm 33 is

mounted pivotally on a bolt 52 preferably threaded in the bracket arm 32 and held in adjusted position by a lock nut 53. The arm 32 has a flat friction surface 55 which engages a fiber disk 56 5 mounted on the bolt 52. Adjacent to the disk 56 is a second disk 57 of inherently resilient compressible material, such as natural or artificial rubber. The latter engages the lower part of the arm 33 from which project pins 58 secured to the arm and passing through the rubber disk and into the fiber disk. By this construction the fiber disk is required to rotate with the arm 33 with its friction surface 60 in frictional engagement with the surface 55 on the bracket arm 32.

The head 61 of the bolt exerts pressure on the 15 arm 33 and by turning the bolt 52 the force derived from the head 61 and transmitted through the compressible disk 57 can be varied to provide the desired frictional contact between surface 55 and 60. A washer 62 between the bolt head and 20 the arm 33 assists in permitting angular motion of the latter around the bolt. Provision is thus made for holding the tube 40 in any position to which it may be moved between upper and lower stop screws 65 and 66 the first of which may be 25 mounted on bracket 28 while the other is held by the loom frame.

In order that the tube 40 may be lowered from its normal raised position I provide an arm 70 supported by and movable about the stud 14 and 30 form therein a slot 71 arcuate with respect to stud 14. A stud 72 secured to the transerrer arm 13 projects through the slot 71 and holds the arm 70 in fixed adjusted position with respect to the transerrer arm by a nut 73. By reason of this 35 connection between the transerrer arm and the arm 70 the latter may be held in any one of a plurality of fixed positions angularly with respect to the transerrer arm and move with the latter. The rear end of arm 70 has a foot 75 the lower 40 part of which is faced with an anti-friction plate 76, such as leather, for engagement with an upper curved part 80 of the tube 40.

In operation, the parts will normally be in the 45 position shown in Fig. 1 with the tube 40 raised and the intake mouth above the thread W extending from the selvage into the shuttle box. When a transfer is called the transerrer arm descends and causes foot 75 of arm 70 to press the forward end of the tube 40 downwardly. This motion 50 embeds the tongue 44 in the pile fabric material, as suggested in Fig. 3, and also places the short lower horizontal section 42 immediately over the pile fabric. This condition exists while the lay is in the forward part of its stroke. Immediately 55 after transfer the transerrer arm 13 will rise during rearward movement of the lay in well-known manner, but the frictional pressure between surfaces 55 and 60 will hold the tube 70 in the down or operating position shown in Fig. 3. As the lay 60 recedes the thread W, held frictionally by the tops of the pile tufts 25, moves toward tongue 44 and to a position under the intake mouth. After the thread is cut as described in my co-pending application Serial No. 190,637, its end remote 65 from the selvage will be free to respond to the tractive force of an inrushing column of air entering the intake mouth. As the lay continues to move rearwardly the thread enters the mouth, being directed toward the latter by the tongue 44. 70

As previously described, the inrush of air is caused by the creation of sub-atmospheric pressures in the rubber tube 48 and the thread is drawn into the tube and held in frictional contact with the curves in the tube joining sections 75

41 and 42, and sections 41 and 46. The thread then extends rearwardly and if long enough wraps around the rear curve 47. The several curves serve to exert a retaining force on the 5 thread additional to that provided pneumatically. This operation occurs while the lay is moving rearwardly and during picking of the replenished shuttle.

As the lay approaches its rear position the re-setting screw 35 engages the web 34 to move the parts pivotally around stud 52 from the position of Fig. 3 back to the position of Fig. 1, thereby raising the section 42 of the tube so that it will be clear of the path of the shuttle.

15 In Fig. 3 the section 42 of the tube is shown spaced slightly above the tops of the pile tufts 25. If however it is desired to have the section 42 descend farther so that its under side will contact with the tufts 25 the set screw 65 will 20 be raised somewhat to permit the relation shown in Fig. 6 when the tube has been lowered on a transferring beat of the loom. In that figure the tops of the tufts are shown as deflected forwardly or to the right because of the pressure of the 25 section 42. This arrangement permits the tube to hold the weft thread W closely against the strip of pile fabric. As the lay moves rearwardly the tufts will appear progressively under the intake mouth 45 and being relieved of pressure 30 will spring upwardly to lift the weft into the mouth where it may be more readily drawn into the tube by the inrushing draft of air as shown in Fig. 6. In this way the resilience of the pile tufts assists in moving the weft thread into the 35 intake mouth.

From the foregoing it will be seen that I have provided a simple form of thread extractor employing a tube supported directly on the arm 33. It will also be apparent that this mode of support 40 provides the several curves which supply additional frictional traction for the thread. It will further be seen that the rubber disk 57 provides convenient means for maintaining sufficient frictional contact with the surfaces 55 and 60 to hold the tube either in its normally raised position or in the operating down position. The stop screw 65 is used as a precautionary measure 45 to prevent breakage of the tube should the section 42 for any reason tend to move to a position too low for correct operation. It will also be seen that the arm 70 is actuated by the trans- 50 ferrer arm 13 but is capable of being held in a plurality of angularly adjusted fixed positions with respect to the transerrer arm and that the foot 75 can therefore engage the tube 40 at different times in the descent of the transerrer arm, depending upon the setting of nut 13. Furthermore, the section 42 serves as a guard to prevent the thread W from moving upwardly out 55 of frictional contact with the pile tufts 25. By referring to Fig. 6 it will also be seen that the tufts of the pile fabric 25 serve to lift the weft thread into the intake mouth during backward motion of the lay.

Having thus described my invention it will be seen that changes and modifications may be made therein by those skilled in the art without departing from the spirit and scope of the invention and I do not wish to be limited to the details 60 herein disclosed, but what I claim is:

1. In a weft replenishing loom having a reciprocating lay with a shuttle box thereon from which a weft thread extends to the selvage, engaging means movable rearwardly with the lay 65 and in engagement with the weft thread to move

the latter rearwardly with the lay, a substantially horizontal tubular member having an intake mouth at its rear end into which a draft of air is drawn during loom operation, said member normally spaced above the thread, means to move the tubular member downwardly against the thread to prevent upward displacement of the latter on replenishing beats of the loom and place the intake mouth behind the thread, the draft of air drawing the thread into the intake 10 and tubular member, rearward motion of the engaging means with the lay moving the thread toward the intake mouth.

2. In a weft replenishing loom having a reciprocating lay with a shuttle box therein from which a weft thread extends to the selvage, engaging means movable rearwardly with the lay and in engagement with the weft thread to move the latter rearwardly with the lay, a tubular member normally spaced above the lay and having an intake mouth in one end thereof into which a draft of air is drawn on a replenishing beat of the loom, means operative on replenishing beats of the loom to move the tubular member to a substantially horizontal position transversely 25 of and immediately over the thread to prevent the latter from moving upwardly and also place the intake mouth behind the thread, rearward motion of the engaging means with the lay moving the thread to a position near the intake 30 mouth and the draft of air drawing the thread into the intake mouth and tubular member.

3. In a weft replenishing loom having a reciprocating lay with a shuttle box therein from which a weft thread extends to the selvage, engaging means movable rearwardly with the lay and in engagement with the weft thread to move the latter rearwardly with the lay, a tubular member normally spaced above the lay and having an intake mouth in one end thereof into which a draft of air is drawn on a replenishing beat 40 of the loom, means operative on replenishing beats of the loom to move the tubular member to a substantially horizontal position transversely 45 of and immediately over the thread to prevent the latter from moving upwardly and also place the intake mouth behind and above the thread, rearward motion of the engaging means with the lay moving the thread to a position under the intake mouth and the draft of air drawing the 50 thread into the intake mouth and tubular member.

4. In a weft replenishing loom having a reciprocating lay with a shuttle box thereon from which a weft thread extends to the selvage, engaging means movable rearwardly with the lay and in engagement with the weft thread to move the latter rearwardly with the lay, a hollow member having an intake mouth into which a draft of air is drawn on replenishing beats of the loom, 60 means to support the member normally in a position spaced above the lay, means operative on a replenishing beat of the loom to lower the member to a position immediately over the thread to prevent movement of the latter upwardly away 65 from the lay and place the intake mouth behind the thread, rearward motion of the engaging means with the lay moving the thread toward the mouth and the latter to be drawn into the intake mouth by the draft of air moving into 70 the mouth, and means to return the hollow member to normal position after a replenishing operation of the loom.

5. In a pneumatic thread extractor for a weft replenishing loom having a lay movable back- 75

wardly and forwardly and having a shuttle from which a thread extends to the adjacent selvage, a mass of deformable material on the lay extending under the thread and having frictional contact with the latter, a tube having a horizontal portion provided with a thread intake mouth at the rear end thereof and extending forwardly over the deformable material and having a draft of air moving into the mouth during loom operation, and means operative on a replenishing beat of the loom to move said horizontal part of the tube to a position adjacent to the deformable material and over the thread to prevent the latter from moving upwardly away from the lay, the last means also operative to place the intake mouth behind the thread, said horizontal part of the tube holding the thread in frictional contact with the deformable material, and rearward motion of the deformable material with the lay moving the thread toward the intake mouth to be drawn into the latter by the draft of air.

6. In a pneumatic thread extractor for a weft replenishing loom having a lay movable backwardly and forwardly and having a shuttle from which a thread extends to the adjacent selvage, a mass of deformable material extending across the lay under and in frictional contact with the thread, a pneumatic tube having a horizontal portion and an intake mouth normally spaced above the deformable material and having a draft of air moving into the mouth during loom operation, and means operative on a replenishing beat of the loom to move the horizontal part of the tube into contact with the deformable material to hold the thread against the latter and also to place the intake mouth behind and above the thread, and rearward motion of the deformable material with the lay moving the thread toward the intake mouth to be drawn into the latter by the draft of air.

7. In a pneumatic thread extractor for a weft replenishing loom having a lay movable backwardly and forwardly and having a shuttle from which a thread extends to the adjacent selvage, a mass of deformable material extending across the lay under and in frictional contact with the thread, a pneumatic tube having a horizontal portion and an intake mouth normally spaced above the deformable material and having a draft of air moving into the mouth during loom operation, means operative on a replenishing beat of the loom to move the horizontal part of the tube into contact with the deformable material to hold the thread against the latter and to place the intake mouth behind the thread, said tube extending upwardly from the forward end of the horizontal part thereof and then rearwardly to provide internal curved surfaces offering frictional resistance to a thread in the tube, and rearward motion of the deformable material with the lay moving the thread toward the intake mouth to be drawn into the latter by the draft of air.

8. In a pneumatic thread extractor for a weft replenishing loom having a lay movable backwardly and forwardly and having a shuttle from which a thread extends to the adjacent selvage, a mass of deformable material extending across the lay under and in frictional contact with the thread, a pneumatic tube having a horizontal portion and an intake mouth normally spaced above the deformable material and having a draft of air moving into the mouth during loom operation, means operative on a replenishing beat of the loom to move the horizontal part of

the tube into contact with the deformable material to deform a portion of the latter and hold the thread against the latter and also to place the intake mouth behind the thread, the exterior of the horizontal part of the tube in engagement with the thread thereunder offering less frictional resistance to the thread than the deformable material and the latter acting during backward motion of the lay to move the thread toward the intake mouth.

9. In a pneumatic thread extractor for a weft replenishing loom having a lay movable backwardly and forwardly and having a shuttle from which a thread extends to the adjacent selvage, a mass of deformable material on the lay extending under the thread and having frictional contact therewith, a tube having a horizontal portion provided with a thread intake mouth at the rear end thereof and extending forwardly over the deformable material, means operative on a replenishing beat of the loom to move said horizontal part of the tube to a position adjacent to the deformable material and over the thread with the intake mouth behind the thread, said horizontal part of the tube holding the thread in frictional contact with the deformable material, and a tongue projecting from the rear of the horizontal part of the tube into the deformable material to guide the thread toward the intake mouth, and rearward motion of the deformable material with the lay moving the thread toward the intake mouth to be drawn into the latter by the draft of air.

10. In a weft replenishing loom having a lay provided with a shuttle box from which a weft end extends to the adjacent selvage, a mass of pile tufts extending transversely of the lay under and in frictional contact with the thread, a pneumatic thread extractor comprising a horizontal member with an intake mouth on the under rear side thereof into which a draft of air is drawn on replenishing beats of the loom, means to hold the extractor in raised position spaced above the thread, means operative on a replenishing beat of the loom to lower the extractor and move the horizontal member into contact with the pile tufts to deform the latter from their normal positions and hold the thread against said tufts, rearward motion of the pile tufts with the lay moving the thread and deformed tuft yarns in engagement therewith to a position under the intake mouth, and the tuft yarns under the mouth thereupon assuming normal position to lift the thread into the intake mouth, and means subsequent to a replenishing operation of the loom to return the extractor to normal position.

11. In a weft replenishing loom having a lay provided with a shuttle box from which a weft thread extends to the selvage, engaging means movable rearwardly with the lay and in engagement with the weft thread to move the latter rearwardly with the lay, a pneumatic thread extractor comprising a tube having a relatively long substantially horizontal section to have sub-atmospheric pressures induced in the rear end thereof, the forward end of the tube being bent downwardly to have a substantially vertical section and then rearwardly to have a relatively short horizontal section in the rear under side of which is an intake mouth, means operative on a replenishing beat of the loom to move the forward end of the tube from normal raised position to low operative position with the intake mouth behind the thread and the under side of the short horizontal section in contact with

- the thread to prevent the latter from moving upwardly away from the lay, rearward motion of the engaging means with the lay moving the thread toward the intake mouth, the thread being drawn pneumatically into the intake mouth and into the interior of the tube along the vertical section and both horizontal sections, said sections providing frictional resistance to the thread tending to hold the latter in the tube.
12. In a weft replenishing loom having a lay provided with a shuttle box from which a weft thread extends to the selvage, engaging means movable rearwardly with the lay and in engagement with the weft thread to move the latter rearwardly with the lay, an arm pivoted to a fixed part of the loom, means to hold the arm in any one of a plurality of different angular positions, a pneumatic thread extractor tube mounted directly on the arm and having a portion extending away from the arm and then downwardly and then toward the lay, the part of the tube extending toward the lay having an intake mouth into which a draft of air is drawn during loom operation, means operative on a replenishing beat of the loom to lower the tube to place the intake mouth behind the thread and place that part of the tube extending toward the lay over the thread, rearward movement of the engaging means with the lay moving the thread toward the intake mouth, and means carried by the lay to engage the arm subsequent to a replenishing operation of the loom to move said arm in a direction to move the tube away from the lay.
13. In a weft replenishing loom having a lay provided with a shuttle box from which a weft thread extends to the selvage, engaging means movable rearwardly with the lay and in engagement with the weft thread to move the latter rearwardly with the lay, an arm pivotally mounted on a part of the loom, means to hold the arm in any one of a plurality of different angular
- positions, a pneumatic thread extractor tube mounted directly on the arm and having an intake mouth into which air is drawn during loom operation, said arm normally holding the tube raised with the intake mouth spaced above the lay, means operative on a replenishing beat of the loom to lower the tube and place the intake mouth behind the thread, rearward motion of the engaging means with the lay moving the thread toward the intake mouth, means acting subsequent to a replenishing operation of the loom to rock the arm in a direction to return the tube to its normally raised position, and means to hold the tube in any one of a plurality of different positions with respect to the arm to place the intake mouth at different distances behind the thread.
14. In a weft replenishing loom having a lay provided with a shuttle box from which a weft thread extends to the selvage, engaging means movable rearwardly with the lay and in engagement with the weft thread to move the latter rearwardly with the lay, a pneumatic thread extractor tube having a normally raised intake mouth into which air is drawn during loom operation, an arm on which the tube is directly mounted, a pivot for the arm, a pair of elements having relatively movable mutually engaging friction surfaces, one of said elements being fixed, means to cause the other element to move with the arm about the pivot, a body of resilient material between the arm and said other element to transmit a yielding force from the arm to said other element, means acting against the friction of said elements to move the tube to a position to place the intake mouth behind the thread, motion of the engaging means with the lay moving the thread toward the mouth, and other means also acting against the friction of said elements to raise the tube to normal position.

RICHARD G. TURNER.
